UNITED STATES PATENT OFFICE.

JOHN F. PEASE, OF SYRACUSE, NEW YORK, ASSIGNOR TO THE JOHN F. PEASE FURNACE COMPANY, OF SAME PLACE.

STEAM-HEATER.

SPECIFICATION forming part of Letters Patent No. 308,039, dated November 11, 1884.

Application filed January 24, 1884. (No model.)

To all whom it may concern:

Be it known that I, JOHN F. PEASE, of Syracuse, in the county of Onondaga, in the State of New York, have invented new and useful 5 Improvements in Steam-Heaters, of which the following, taken in connection with the accompanying drawings, is a full, clear, and exact description.

This invention relates more particularly to 10 steam-heating apparatus employed for heating buildings.

The chief object of this invention is to facilitate the return of the water of condensation to 15 the water-space of the boiler; and to that end my invention consists in the construction and combination of parts, hereinafter described, and specifically set forth in the claim.

In the annexed drawings, Figure 1 is a vertical section of a heating apparatus embodying my invention, taken on line *x x* in Fig. 2, 20 and Fig. 2 is a horizontal section on line *y y*, Fig. 1.

Similar letters of reference indicate corresponding parts.

25 A denotes the fire-box, upon which is erected a combustion-chamber, D, which communicates at its upper end with a radiator, R, surrounding the combustion-chamber, as shown in Fig. 2 of the drawings. The products of 30 combustion pass from the combustion-chamber D through pipes G into the radiator R, and thence escape through the exit-flue E connected with the said radiator. A direct exit-flue, F, is connected with the upper part 35 of the combustion-chamber and provided with a damper to increase the draft through the fire-box, when required.

The described fire-box, combustion-chamber, and radiator are inclosed in a casing, C, 40 which admits air at its base, said air becoming heated in its ascent to the top of the casing, from whence it is conducted by pipes P P to the apartments of the building to be heated.

The aforesaid apparatus constitutes a hot-air furnace for which I have already obtained 45 United States Letters Patent, dated July 10, 1877. With said hot-air furnace I have combined a steam-heating apparatus consisting of a tubular upright boiler, B, supported inside 50 of the combustion-chamber in such a manner

as to cause the products of combustion to circulate around it as well as through it, for which arrangement I have also obtained Letters Patent of the United States, November 1, 1881. A pipe, a, extended from the top of the boiler 55 conveys the steam to radiators in the apartments of the building to be heated, and another pipe, c, conducts the water of condensation from the radiators back to the boiler.

It is to promote the flow of the water of condensation to the water-space of the boiler which my present invention has for its object, and to accomplish this I extend the return water-pipe c into the fire-box A in such a position as to cause it to be impinged by the 60 fire, and thence I extend it vertically to the bottom of the boiler B, which it taps at or near its center, as illustrated in Fig. 1 of the drawings. The bottom b of the boiler I incline from the fire-door H toward the opposite side 65 of the fire-box, so as to counteract the tendency of the fire in the aforesaid direction, and thus better distribute the circulation of the products of combustion around and through the boiler B. The lowest point of the inclined 70 bottom b of the boiler I tap by an auxiliary pipe, d, which extends out of the combustion-chamber above the fire-box and out through the casing C, at the outside of which latter I connect said auxiliary pipe with the water-induction pipe c, before described.

It will be observed that by the aforesaid arrangement of the auxiliary pipe d the water-induction pipe communicates with the water-space of the boiler at two points at relatively 85 different elevations. The pipe c, tapping the boiler at the higher point and being extended through the fire-box, is subjected to intense heat, and the water in said pipe is thus rapidly expanded and driven up into the boiler, 90 while the pipe d, tapping the boiler at its lowest point, draws therefrom the coolest water, which rushes to the pipe c and toward the aforesaid heated portion thereof, to follow the current produced by the displacement of the 95 water in said pipe incident to the heat received from the fire surrounding it.

The described circulation of water produces suction in the main portion of the pipe c, which is extended to the radiator, and this 100

suction promotes the flow of the water of condensation from the radiator to the water-space of the boiler.

The aforesaid circulation of water from the boiler through the pipes *d* *c* back to the boiler also tends to cleanse the boiler, the sediments being constantly drawn off through the pipe *d* and into the pipe *c*, from whence they can be removed by opening a blow-off cock, *e*, connected to a branch of the said pipe, as illustrated in Fig. 1 of the drawings.

Having described my improvements, what I claim is—

In combination with the fire-box *A*, the boiler *B*, provided with the inclined bottom *b*, and with the steam-pipe *a*, the return water-

pipe *c*, extended into the fire-box and tapping the inclined bottom of the boiler at or near the center thereof, and the auxiliary pipe *d*, tapping the lowest point of the aforesaid inclined bottom and communicating with the water-induction pipe, substantially in the manner described and shown.

In testimony whereof I have hereunto signed my name and affixed my seal, in the presence of two attesting witnesses, at Syracuse, in the county of Onondaga, in the State of New York, this 17th day of January, 1884.

JOHN F. PEASE. [L. S.]

Witnesses:

FREDERICK H. GIBBS,
WILLIAM C. RAYMOND.
